[57] CLAIM

The ornamental design for a molded tool case, as shown and described.

DESCRIPTION

FIG. 1 is a top perspective view of a molded tool case showing our new design;

FIG. 2 is a front elevational view;

FIG. 3 is a left side elevational view;

FIG. 4 is a rear elevational view;

FIG. 5 is a right side elevational view;

FIG. 6 is a bottom plan view; and

FIG. 7 is a perspective view thereof showing the molded tool case in an open position.

*FIG.3**FIG.1**FIG.2**FIG. 5**FIG. 4**FIG. 6**FIG. 7*
